UNITED STATES PATENT OFFICE.

BURT E. TAYLOR, OF MOUNT VERNON, NEW YORK, ASSIGNOR TO THE BORDEN COMPANY, OF NEW YORK, N. Y., A CORPORATION OF NEW JERSEY.

APPARATUS FOR WASHING CANS AND THE LIKE.

Application filed October 28, 1924. Serial No. 746,265.

The invention relates to an improvement in apparatus for washing cans and the like.

In apparatus especially adapted for washing or cleansing the interior of such articles as cans for containing and shipping milk, it has been found that a reciprocating nozzle or spray head is an efficient means of directing the washing fluid or liquid to all parts of the insides of the cans. Usually the cans to be washed are placed upside down on a runway along which the cans are fed with an intermittent motion. As the cans are advanced they are successively positioned over different nozzles or spray heads by which the successive steps or stages of the washing operation are performed. When a reciprocating nozzle is used the supply of washing fluid is usually shut off during the time the cans are traveling from one station to the next, during which time the nozzle remains in retracted position. When a can is positioned over the reciprocating nozzle and the latter is actuated to enter the can, substantially simultaneously therewith the supply of washing fluid is turned on to be directed against the side walls and bottom of the can while the nozzle is rising in the can and being retracted therefrom.

The object of the present invention is to provide improved and simplified means for actuating the reciprocating nozzle and supplying it with the washing or cleansing fluid or liquid. The invention consists in arranging the intake pipe through which the fluid or liquid is fed to the nozzle so that an equalized or balanced pressure will be maintained in the intake pipe whatever the position of the nozzle. To this end the intake pipe is provided with open ends which are immersed in a bath of the washing fluid or liquid (fed by the liquid supply means) as the intake pipe moves with the reciprocating nozzle. By this arrangement the back pressure or "thrust" in the pipes is lost or taken up in the bath in which the ends of the intake pipe are immersed. As a result of maintaining a balanced or equalized pressure in the pipes which supply the washing fluid to the reciprocating nozzle it is simply necessary to expend sufficient energy in reciprocating the nozzle and the pipes to overcome inertia and friction.

This principle of operation is believed to be broadly novel, and although it is shown

and described as particularly adapted for use in connection with can washing apparatus, it will be understood that the invention is not to be restricted to this purpose since it is adapted for use in connection with other kinds of apparatus in which a fluid or liquid delivering or discharging means is caused to move while the fluid or liquid is being discharged, whether in the form of a spray or otherwise. The invention itself is more fully described hereinafter and is particularly pointed out in the appended claims.

In the accompanying drawings illustrating the preferred form of the invention, Fig. 1 is a side elevation of so much of a can washing machine as is necessary to illustrate the application of the apparatus of the present invention thereto; Fig. 2 is a plan of the parts shown in the right hand end of Fig. 1; and Fig. 3 is a side elevation, on an enlarged scale, of the reciprocating nozzle and the parts connected therewith, with the intake pipe and the reservoirs shown in section.

The can washing or cleansing machine to which the present improvements are adapted to be applied may be of any usual or preferred construction and mode of operation. One such can washing or cleansing machine is shown and described in Patent No. 1,309,785, granted to me July 15, 1919. In that machine the cans are positioned upside down on a horizontal runway and are advanced intermittently into position for the various washing operations, the washing or cleansing liquid being introduced into the cans during the temporary pauses. In the accompanying drawings is shown so much of the machine illustrated in said patent as is necessary to understand the mode of operation of the present improvements.

The articles to be washed or cleansed (in this instance the milk cans 5) are positioned upside down on the can runway 6 and advanced intermittently therealong. The can runway 6 comprises two horizontally disposed angle irons 7, the upstanding side walls 8 of which serve as guides to prevent the lateral displacement of the cans. The angle irons 7 rest on the horizontally disposed bars 9 which in turn rest on the transverse pieces 10 supported from the frame

work 11 of the can washing machine. Means for intermittently advancing the cans upside down along the can runway 6 are shown and described in said patent. It is sufficient for present purposes to understand that a line of cans is advanced intermittently along the can runway, and that during the pauses the washing or cleansing fluid or liquid is introduced into the interior of the cans. In the accompanying drawings the cans 5 are shown as halted for one of the washing or cleansing operations.

The improved can washing apparatus of the present invention is provided with a nozzle 12 carried by the upper or free end of a vertically-disposed discharge pipe 14 adapted to be inserted within the can and to be withdrawn therefrom, as indicated by the dotted lines in Fig. 3. The nozzle 12 is so shaped as to direct numerous small streams of the washing liquid to most effectively reach all parts of the interior surfaces of the can. The discharge pipe 14 is connected by means of a T nipple 15 with the middle part of an intake pipe 16 which is open at its two ends 17 and 18. The connections between the discharge pipe 14 and the intake pipe 16 consist of the pipes 19 and 20, nipple 21, and their connecting elbow joints, all as clearly shown in Fig. 3.

In the illustrated embodiment of the invention the intake pipe 16 is mounted to reciprocate vertically. For this purpose the intake pipe is connected with a cam 24 eccentrically mounted on the shaft 25 which may be driven from any convenient source of power. The cam groove 26 engages the roll 27 mounted on the outer end of the lower arm 28 of a bell crank lever pivoted at 29, the other arm 30 of which is connected by the link 31 with the vertical arm 32 of a second bell crank lever mounted on the shaft 33 journaled in the bracket 34. The long off-set arm 35 of the second bell crank is pivotally connected by means of the link 36 with a bar 37 which extends from the T nipple 15 to the corresponding T nipple 38 of the intake pipe 39. The intake pipe 39 and its associated parts are the same in construction and operation as the intake pipe 16 and its associated parts.

The washing or cleansing fluid or liquid is supplied to the intake pipe 16 in such manner that there is always a balanced or equalized pressure in the pipe as it reciprocates vertically during the insertion of the nozzle 12 into the can to be washed and its withdrawal therefrom. For this purpose the upper section 41 of the intake pipe is arranged to be received within a chamber or reservoir 42 secured to the frame work of the machine, and the lower section 43 of the intake pipe is arranged to be received within the chamber or reservoir 44 also secured to the frame

work of the machine. A liquid-tight joint is secured between the section 41 and the reservoir 42 by means of the stuffing box 45 and a liquid-tight joint is secured between the section 43 and the reservoir 44 by the 70 stuffing box 46. The washing or cleansing fluid or liquid, which in this instance may be regarded as water, is intermittently introduced into the lower reservoir 44, in timed relation with the rise and fall of the nozzle 75 12, through a supply pipe 48.

In the supply pipe 48 is located a valve 49 with the stem 50 of the movable valve part 56 projecting downwardly in position to be engaged and raised by the active part 51 of the cam 52 mounted on the shaft 53 journaled in the brackets 54, one of which is supported from the reservoir 44 and the other of which is supported from the reservoir 55. The shaft 53 may be actuated from any convenient source of power in timed relation with the actuation of the shaft 25. The valve 49 is of usual construction and mode of operation, the arrangement being 85 such that when the movable part 56 carrying the stem 50 is lifted by the engagement of the cam part 51 therewith, the valve 49 is opened to admit water or other wash fluid into the reservoir 44. The actuation of the shaft 53 being in timed relation with the actuation of the shaft 25, the cam part 51 is in effective relation with the valve stem 50 while the nozzle 12 is being inserted into and retracted from the can.

When the line of cans passing through the machine is halted with a can 5 in position over the nozzle 12 of the apparatus of the present invention, the rotation of the cam 24 causes the discharge pipe 14 and the nozzle 12 to rise into the can. As the nozzle 12 enters the can, the valve 49 which controls the supply of wash liquid to the reservoirs is actuated to cause liquid under pressure to be forced out through the perforations in the nozzle 12, as shown by the broken lines in Fig. 3. The liquid which enters the upper part of the lower reservoir 44 through the pipe 48 passes up through the sections 43 and 41 of the pipe 16 and into the upper reservoir 42. The greater part of the liquid which passes up through the section 43 (after the reservoir 42 and the section 41 have once been filled) passes through the pipes 20 and 19 into the discharge pipe 14 and out through the nozzle 12. When the valve which controls the flow of liquid through the supply pipe 48 is opened, putting the liquid in the reservoirs and the pipes connected therewith under pressure, the back pressure from the nozzle 12 in the pipes 14, 19 and 20 is evenly distributed through the intake pipe 16 into the reservoirs 42 and 44. Thus there is a balanced pressure in the sections 41 and 43 of the intake pipe as the latter reciprocates. Consequently the mechanism for raising and

lowering the intake pipe and the parts connected with it is compelled to overcome only the action of gravity and the friction of the stuffing boxes.

5 Having thus described the invention what I claim as new is:—

1. An apparatus for washing cans and the like comprising a nozzle, a pipe connected with the nozzle having two inlet openings, 10 a reservoir in which one inlet opening is located, a second reservoir in which the other inlet opening is located, means for intermittently supplying one of the reservoirs with liquid, and means for actuating the pipe 15 to move the nozzle to desired positions.

2. An apparatus for washing cans and the like comprising, an upright pipe having a nozzle at its upper end, a vertically arranged intake pipe connected with the nozzle pipe, 20 said intake pipe being open at its upper and lower ends, a reservoir in which the upper end of the intake pipe is located, a second reservoir in which the lower end of the intake pipe is located, means for intermittently admitting liquid to one of the reservoirs, and means for raising and lowering the pipes.

3. An apparatus for washing cans and the like comprising, an upper reservoir, a lower 30 reservoir, a vertically arranged intake pipe having its upper end loosely connected with the upper reservoir and its lower end loosely connected with the lower reservoir, means for reciprocating the intake pipe, means for intermittently supplying one of the reservoirs with liquid under pressure, and a discharge pipe having a nozzle at its outer end connected with the intake pipe.

4. An apparatus for washing cans and the 40 like comprising, two reservoirs spaced apart, an intake pipe arranged with one end loosely connected with one reservoir and the other end loosely connected with the other reservoir, means for reciprocating the intake pipe, means for supplying one of the reservoirs with liquid under pressure, and a dis-

charge pipe carrying a nozzle at its free end connected with the intake pipe.

5. An apparatus for washing cans and the like comprising, an intake pipe having at each end an inlet opening, each end of the intake pipe being located in a reservoir, means for supplying the intake pipe with liquid under pressure, means for actuating the intake pipe to cause its two ends to travel through the liquid in which they are immersed, and a discharge pipe connected with the intake pipe.

6. An apparatus for discharging liquid comprising, an intake pipe having at each end an inlet opening, means for containing liquid in which the two ends of the intake pipe are immersed, means for actuating the intake pipe to cause its two ends to move through the liquid, means for intermittently supplying fresh liquid to the liquid containing means, and a discharge pipe connected with the intake pipe.

7. An apparatus for discharging liquid through a reciprocating nozzle comprising, an intake pipe having at each end an inlet opening, means for containing liquid in which the two ends of the intake pipe are immersed, means for reciprocating the intake pipe, means for intermittently supplying fresh liquid to the liquid containing means, and a discharge pipe carrying the nozzle at its free end connected with the intake pipe.

8. An apparatus for washing cans and the like comprising, a vertically arranged intake pipe having at each end an inlet opening, means for reciprocating the intake pipe, an upper reservoir in which the upper end of the intake pipe travels, a lower reservoir in which the lower end of the intake pipe travels, means for intermittently supplying fresh liquid to one of the reservoirs, and a vertically arranged discharge pipe carrying a nozzle on its free end connected with the middle of the intake pipe.
